UNITED STATES PATENT OFFICE

DANIEL OTIS DE LOACH, OF SAVANNAH, GEORGIA

NUTCRACKER

Application filed December 14, 1929. Serial No. 414,188.

This invention relates to nut cracking devices and pertains particularly to a device adapted to be secured to a table or other suitable support so that it may be firmly held in position during the actuation of the operating lever thereof.

The primary object of this invention is to provide a nutcracker employing a plunger and operating lever therefor in which the lever may be adjusted with respect to the plunger which it controls so as to adapt the machine to nuts of different sizes, making it possible to crack any size nut easily and without damaging the meat thereof.

Another object of the invention is to provide a nutcracker employing a fixed jaw and a plunger carrying a movable jaw between which jaws in a plane beneath the same is disposed an adjustable trough in which the nuts may be caught after the shell has been cracked and the nut released by the plunger, this trough being so formed as to carry the nut off to one side of the machine into a receiver.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claim.

In the drawings:—

Figure 1 is a view in front elevation of the nutcracker embodying the present invention.

Figure 2 is a view partly in side elevation and partly in section of the machine.

Figure 3 is a sectional view taken substantially upon the line 3—3 of Figure 2.

Figure 4 is a sectional view taken substantially upon the line 4—4 of Figure 2.

Figure 5 is a sectional view taken upon the line 5—5 of Figure 1.

Referring more particularly to the drawings wherein like numerals of reference indicate corresponding parts throughout the several views, the numeral 1 indicates gen-

erally the body of the present machine, this body being preferably cast in one piece. The body 1 consists of an elongated flat base portion 2 at one end of which an integral depending bar 3 is formed which terminates in an inwardly extending arm 4 disposed beneath and parallel with the base 2 as shown, this arm 4 constituting the clamp arm of the machine.

A threaded passage 5 is formed through the clamp arm 4 to receive a clamp screw 6 the upper end of which has swivelly mounted thereon a head 7 the upper face of which is covered by a suitable body 8 such as rubber or fiber which will prevent marring of a table surface when the screw is forced thereagainst. The lower end of the screw carries the wings 9 which facilitate its being turned into position.

The base 2 has cast integral therewith at the end opposite the depending portion 3 the upstanding fixed jaw 10, the inner face of which is provided with a circular recess 11 in which a portion of a nut positions when placed in the machine to have the shell thereof cracked.

At the opposite end of the base the spaced upstanding plates 12 are formed through the center of each of which a screw hole 13 is drilled, one thereof being provided with screw threads. Adjacent the forward edges of the plates 12 there is secured therebetween and in vertically spaced relation to the portion 14 of the base which portion has its upper surface in a higher plane than the portion 85 of the base lying between the plates and the fixed jaw 10, is a block 15 leaving a space 16 between the plates 12 through which a plunger 17 may move, this plunger resting upon the bottom portion 14 and snugly fitting between the plates as shown.

The upper face of the plunger 17 is toothed forming the rack 18 and at the forward end the plunger carries a head 19 constituting a shiftable jaw, the forward face of the head 19 being recessed slightly as at 20 to receive and more firmly engage the shell of a nut.

A relatively long plunger actuating lever 21 is provided at one end of which is carried a pinion 22 which positions between the plates 10.

12 and receives through the central opening 23 the pivot pin 24 which extends through the apertures 13 and threadably engages at one end in the threaded one of these apertures. At its other end the pin 24 carries the wings 25 by which its rotation is facilitated when its removal is desired.

10 The inner edge of one of the plates 12 and the opposing portion of the inner face of the fixed jaw 10 carries a lug 26. At the opposite side of the fixed jaw 10 and upon the other of the plates 12 in the edge opposing the fixed jaw there is formed a pair or more of screw holes 27.

15 Adapted to position between the plates 12 and the fixed jaw 10 is a trough 28 which has a bottom 29 and an upstanding flange 30 along one longitudinal edge, each end edge of the bottom having adjacent the forward edge thereof the upstanding side plates 31 which position against the inner face of the jaw 10 and the inner edge of the plate 12 in which the screw hole is formed, each of these plates 31 having an aperture 32 therethrough 20 for the passage of a holding screw 33 by means of which the trough is maintained in position. The up-turned rear portion or flange 30 of the trough positions against the lugs 26 and is held thereby against oscillation 25 on the screws 33.

20 From the foregoing description it will be readily apparent that by removing the pivot pin 24 the pinion 22 may be disengaged from the plunger 17 so as to permit the plunger 35 to be shifted to a desired adjusted position after which the pinion may be replaced and the operation of the machine carried out.

30 In this manner the machine can be adjusted to receive nuts of different sizes, so that the correct amount of pressure may be applied 40 to the shells to effect the breaking thereof without damaging the meats.

45 The trough 28 assists in maintaining the nut in place and acts to discharge the cracked nut to one side of the machine when the plunger is retracted. This trough may be adjusted also to accommodate the particular size nut upon which the machine is being used.

50 Having thus described my invention, what I claim is:—

55 A nut cracking machine comprising a base, means for securing the base in working position, a fixed jaw carried by the base, spaced upstanding plates disposed on the base in spaced relation to the fixed jaw, a plunger formed to provide a rack shiftably mounted between said plates and having a head constituting a shiftable jaw adapted to move relative to the fixed jaw, a block disposed between the plates above the plunger maintaining the latter in position, a gear pinion pivotally mounted between the plates for engagement with the rack, a lever carried by the pinion having its movement limited to said

block, a nut supporting trough disposed between the fixed jaw and the opposed edges of said plates comprising a bottom, a back flange and end flanges one arranged against the fixed jaw and the other arranged against a plate, means for securing the end flanges to the adjacent bodies, abutment lugs for said back flange carried upon the opposing faces of the fixed jaw and plate, and vertically adjustable supporting members passing through said end flanges, one thereof being mounted in the fixed jaw and the other being mounted in a plate.

60 In testimony whereof I hereunto affix my signature.

DANIEL OTIS DE LOACH.
